WILLIAM M. HEPBURN, OF TOLEDO, OHIO, ASSIGNOR TO THE SURFACE COMBUSTION CO., OF TOLEDO, OHIO, A CORPORATION OF NEW YORK

GAS BURNER

Application filed April 24, 1929. Serial No. 357,707.

This invention relates to apparatus for forming and burning self-sustaining mixtures of fuel gas and air and has for its object to provide an apparatus of the character indicated which shall have special utility in connection with industrial furnaces. Another object is to provide, in connection with apparatus adapted to form and burn self-sustaining mixtures of fuel gas and air,

10 a simple and practical means for lighting said mixture which means shall also be adapted to supply to the furnace a given amount of heat tending to hold the furnace at a given temperature after the main heating apparatus has brought the furnace up to temperature. Other objects will 15 more fully appear hereinafter.

Referring to the drawing wherein the preferred form of the invention is shown, the 20 single figure thereof is an axial section through the burner apparatus which is shown as positioned in the wall of furnace chamber.

In the drawings, 10 indicates the wall of 25 a furnace chamber. The outer face of the wall is recessed to provide a seat for a dished casing 12 within which the major portion of the burner apparatus is housed the casing being substantially closed by a plate 14 having a central opening 16 through which atmospheric air may reach the burner when a 30 damper or shutter 18 associated therewith is open as it normally is when the burner is in operation, the primary purpose of the 35 shutter being to prevent the entry of air into the furnace when the burner is not in operation.

20 indicates a combustion tunnel which opens into the furnace chamber of which 40 the wall 10 forms a part. This tunnel is preferably formed within a body of refractory material 22 contained within a tubular casing 24 which is removably positioned within a suitable opening in the furnace wall. The tunnel at its inlet end is provided with a relatively restricted throat 26 which is of substantial length and preferably of uniform diameter. At the discharge end of the throat the tunnel is of materially greater diameter and tapers outwardly

whereby the combustible mixture issuing from the throat may have its velocity reduced sufficiently to enable it to burn within the expanding portion of the tunnel.

The self-sustaining mixture of gas and air to be burned in the tunnel is formed by allowing a jet of fuel gas under relatively high pressure to entrain air in two stages, the air entering through the opening 16 in the casing plate 14 as previously stated. Fuel gas from a suitable source of supply and under suitable pressure is delivered to a conduit 27 having at its discharge end a jet orifice nozzle 28 from which the gas is jetted across an intervening air space into an entraining tube 30 which in turn discharges across an intervening air space into the throat 26 of the combustion tunnel. The jet orifice nozzle 28, the tube 30 and throat 26 are of such relative diameters and so positioned with respect to each other that by the time the gas enters the expanding portion of the combustion tunnel it has entrained sufficient air in passing across said intervening air spaces to form with the air an explosive or self-sustaining mixture.

The entraining tube 30 and the conduit 27 which carries the gas jet orifice nozzle 28 must of course be supported in relatively fixed position with respect to the throat 26 of the combustion tunnel. This supporting means takes the form of an open ended body 32 adapted to project through an opening in the bottom of the casing 12 and form the mouth of the combustion tunnel. Projecting from the outer face of the body 32 is a spider-like structure 34 having axially spaced hubs 36 and 38 wherein the conduit 27 and entraining tube 30 are respectively supported. For obvious reasons it is of the first importance that the combustible mixture be not allowed to flow unburned from the combustion tunnel. An ordinary lighting pilot is impractical because it would be quickly snuffed out by the strong draft. The present invention overcomes the lighting problem in a novel and practical manner as will now be explained.

Supported by the body 32 is a plurality, preferably a pair, of pilot burners 40 of a

type adapted to burn explosive gaseous mixtures, the burners being mounted in cored bosses 42 formed on the opposite inner sloping walls of the body, the burners being supplied with an explosive mixture of fuel gas and air from a supply conduit 44 which delivers into a distributing manifold 46 formed in the body. The explosive mixture supplied to the conduit is derived from a

10 source of supply exteriorly of the air chamber formed by the casing 12, the mixture being formed by any suitable means not shown. The pilot burners are cylindrical bodies each

15 having a restricted annular feed passage 48 therethrough formed in any suitable manner as by a plug of reduced diameter con-

centrically positioned within the body. The annular feed passage discharges into a relatively short well formed in the body by

20 having the central plug therein terminate short of the end thereof, the well having an undercut 50. The purpose of the undercut in the well is to cause the combustible mixture which issues from annular feed passage

25 48 in tubular form to swirl violently within the confines of the well in order that it may start to burn therewithin. The mixture burns at the tip of the burner with a short blue flame which is practically impossible to blow off. The pilot burners are so positioned as to direct the flame therefrom

toward the inlet to the throat 26 of the combustion tunnel, the axis of the burners being preferably so positioned that if projected

30 they would intersect at a point adjacent the discharge end of the throat. It is self-evident that the combustible mixture dis-

35 charged into said throat and formed by the jet of gas issuing from the jet orifice 28 will be ignited by the flames from the pilot burn-

40 ers.

The pilot burners serve not only to light the combustible mixture entering the combustion tunnel, but also as auxiliary burners for

45 continuously supplying heat to the furnace chamber of which the wall 10 forms a part after the main burner is shut off, the heat so supplied tending to keep the furnace chamber up to temperature. The import-

50 ance of this will be readily appreciated when it is remembered that after a furnace is once up to temperature a relatively small amount of heat is required to hold it at that temperature. When the main burner is

55 shut off as when the furnace is up to temperature the air shutter 18 will of course be closed to prevent air from entering the furnace chamber. Since the combustible mix-

60 ture supplied to the combined auxiliary and pilot burners 40 is explosive it will of course burn in an atmosphere devoid of air or oxygen and hence the closing of the air shutter 18 has no effect on the operation of said burners.

The inner walls of the dished casing 12 are

provided with heat conducting fins at webs 52 which absorb heat transmitted through the furnace wall. The air entering through the shutter controlled inlet 16 absorbs heat from the fins 52 and is therefore somewhat preheated and additionally serves to cool the casing 12.

What is claimed is:

1. In apparatus for forming and burning self-sustaining mixtures of fuel gas and air, the combination of a combustion tunnel having a relatively restricted throat at its inlet end, an entraining tube set to discharge into said throat across an intervening air gap, a jet orifice nozzle set to discharge into said tube across an intervening air gap, means for supplying fuel gas to said nozzle, a plurality of burners adapted to burn self-sustaining mixtures of fuel gas and air and set to discharge across the first mentioned air gap from points on opposite sides of the axis of the entraining tube in advance of the gap, and means for supplying a self-sustaining mixture of fuel gas and air to said burners.

2. In apparatus for forming and burning self-sustaining mixtures of fuel gas and air, the combination of a combustion tunnel having a relatively restricted throat at its inlet end, an entraining tube set to discharge into said throat across an intervening air gap, a jet orifice nozzle set to discharge into said tube across an intervening air gap, means for supplying fuel gas to said nozzle, a plurality of burners adapted to burn self-sustaining mixtures of fuel gas and air and set to discharge across the first mentioned air gap from points on opposite sides of the axis of the entraining tube in advance of the gap, and means for supplying a self-sustaining mixture of fuel gas and air to said burners, and means adapted to close off the air through said throat.

3. In apparatus for forming and burning self-sustaining mixtures of fuel gas and air, the combination of a combustion tunnel having a relatively restricted throat at its inlet end, an entraining tube set to discharge into said throat across an intervening air gap, a jet orifice nozzle set to discharge into said tube across an intervening air gap, means for supplying fuel gas to said nozzle, a burner adapted to burn a self-sustaining mixture of fuel gas and air positioned laterally of the entraining tube intermediate between said gaps and set to discharge into said throat, and means for supplying a self-sustaining mixture of fuel gas and air to said burner.

4. In apparatus for forming and burning self-sustaining mixtures of fuel gas and air, the combination of a combustion tunnel having a relatively restricted throat at its inlet end, an entraining tube set to discharge into said throat across an intervening air gap, a jet orifice nozzle set to discharge into said

5 tube across an intervening air gap, means for supplying fuel gas to said nozzle, unitary means common to both air gaps for cutting off air supply thereto, and means for burning a self-sustaining mixture of fuel gas and air in front of said throat in a manner to allow the combustion products resulting from such burning to enter said tunnel.

10 5. In apparatus for forming and burning self-sustaining mixtures of fuel gas and air, the combination of means forming a chamber having an inlet for air, a combustion tunnel communicating with said chamber, an entraining tube within the chamber set to discharge into said tunnel across an intervening air gap, a jet orifice nozzle within the chamber set to discharge into said tube across an intervening air gap, means for supplying fuel gas to said nozzle, and unitary means adapted to close said chamber inlet to cut off the air supply to both of said air gaps.

15 6. In apparatus for forming and burning self-sustaining mixtures of fuel gas and air, the combination of means forming a chamber having an inlet for air, a combustion tunnel communicating with said chamber, an entraining tube within the chamber set to discharge into said tunnel across an intervening air gap, a jet orifice nozzle within the chamber set to discharge into said tube across an intervening air gap, means for supplying fuel gas to said nozzle, means within said chamber adapted to burn a self-sustaining mixture of fuel gas and air in a manner to discharge the burning mixture into said tunnel, and means for supplying a self-sustaining mixture of fuel gas and air to said means.

20 7. In apparatus for forming and burning self-sustaining mixtures of fuel gas and air, the combination of means forming a chamber having an inlet for air, a combustion tunnel communicating with said chamber, an entraining tube within the chamber set to discharge into said tunnel across an intervening air gap, a jet orifice nozzle within the chamber to set to discharge into said tube across an intervening air gap, means for supplying fuel gas to said nozzle, and means within the chamber for imparting heat to the incoming air.

25 8. In apparatus for forming and burning self-sustaining mixtures of fuel gas and air, the combination of a furnace having a recess in its wall with a combustion tunnel leading from said recess to the interior of the furnace, means defining a chamber within said recess, an entraining tube within said chamber set to discharge into said tunnel across an intervening air gap, and a jet orifice nozzle within said chamber set to discharge into said tube across an intervening

air gap, said chamber having an air inlet and supplying air to both of said air gaps.

In testimony whereof I affix my signature.
